[57] CLAIM

The ornamental design for a set of moveable notational figures for musical scale, as shown and described.

DESCRIPTION

FIG. 1 is a perspective view of a set of moveable notational figures for musical scale showing my new design. FIG. 2 is a side elevational view of one of the figures taken along the line 2—2 of FIG. 1. The backs of the figures are flat and unornamented.
